UNITED STATES PATENT OFFICE.

JAMES P. RATIGAN, OF WALNUT PARK, CALIFORNIA.

BEAM HANGER.

Application filed April 13, 1925. Serial No. 22,768.

This invention relates to a portion of the means employed for connecting walking beams or other fulcrumed operating members to the polish rods of deep well pumps and is commonly known as a beam hanger.

An object, in general, of the invention is to effect rotation of the sucker rods so as to rotate the plunger. Such rotation tends to prevent buckling of the rods, as the twist takes up the slack, and also tends to prevent unscrewing of the rods and insures evenness of wear on the pump plunger and barrel.

Another object is to effect the rotation by a comparatively simple construction.

Another object is to insure rotation even though the stroke of the walking beam may be comparatively short.

Another object is to so construct the hanger that, if the plunger or sucker rods should be sanded up, the hanger will not rotate the sucker rods and twist them off.

A further important object is to minimize side thrust of the polish rod in the stuffing box as the walking beam swings up and down. Ordinarily such side thrust is present to a large extent on the down stroke of the walking beam, as the stuffing box tends to hold the polish rod in axial alignment with the stuffing box while the walking beam, swinging in an arc, tends to move the upper end of the polish rod out of actual alignment with the stuffing box as the walking beam approaches the upper and lower ends of its stroke.

Further objects and advantages will appear in the subjoined detailed description.

The accompanying drawings illustrate the invention:

Fig. 1 is a side elevation of a beam hanger constructed in accordance with the provisions of this invention. A fragment of the polish rod is shown, together with the polish rod grip and the cable connecting said grip to the beam hanger. Also fragments of the operating member and its support are shown.

Fig. 2 is a view of the beam hanger corresponding to the showing in Fig. 1, but on a larger scale, a fragment of the operating member being indicated in dotted lines.

Fig. 3 is an elevation of Fig. 2 from the right thereof.

Fig. 4 is a plan view, partly in section, from the line indicated by 4—4, Fig. 2.

Fig. 5 is a fragmental side elevation of a modified form of the invention, the operating member being indicated in broken lines.

Fig. 6 is a fragmental side elevation of another modification of the invention.

Fig. 7 is a side elevation of a further modification of the invention.

Referring first to the form of the invention shown in Figs. 1 to 4, inclusive, there is provided a sectional stem, an upper section 11 and lower section 12. The upper section 11 may be rigidly secured in any well known manner to the operating member, indicated at *a* in Fig. 1 as a walking beam, so as to constitute a downwardly projecting arm of said walking beam; or the section 11 may be mounted in such fashion that it will tend to rock slightly on the walking beam as the walking beam swings up and down. The rocking of the section 11 on the walking beam should be more or less limited in extent, and, accordingly, in the present instance the stem section 11 is provided with a head 13 having laterally extending flanges with flat under faces 14 which loosely rest on the upper face of the walking beam. The section 11 extends through the usual slot *b* in the end of the walking beam.

The sections 11, 12 are pivotally connected at 15 so that as the walking beam swings up and down the section 12 will tend to remain in axial alignment with the polish rod, indicated at *c* in Fig. 1. Especially is this true on the downstroke of the pump plunger, since said plunger is automatically lowered by the weight of the sucker rods and superposed column of liquid, and the walking beam exerts no pressure on the polish rod because of the jointed construction of the section 11, 12 and the section 11 being swingingly suspended from the walking beam. Preferably the head is provided with an eye 16 with which hoisting tackle may be connected when it is desired to assemble the beam hanger on the walking beam or remove it therefrom.

Any suitable means may be provided operable by relative swinging of the stem sections to effect rotation of the polish rod and such means, in this instance, are constructed as follows: The lower portion 17 of the section 11 preferably constitutes a leg that extends at an angle to the upper portion thereof and overlaps the lower section 12 and is provided at its lower end with a pawl or

pawls 18 which are pivoted at 19 to the section 11. The pawls 18 are adapted to engage teeth 20 formed in the upper face of a rotatably mounted member 21. In the 5 present instance the teeth 20 are in several concentric series, there being a series for each of the pawls, and the teeth of the different series are in staggered relation and the progressive arrangement of the teeth is 10 such that only one of the teeth is engaged by a pawl at one time and the several pawls engage the teeth successively. Thus, if the teeth in each series are spaced, for example, half an inch apart, and there are four series of teeth, approximately one-eighth of an inch peripheral movement of the member 21 will be effected by each of the pawls 18 if the extent of the movement of the pawls is less than one-half inch.

20 The member 21 is rotatably mounted on the stem section 12 by reason of said section having a nut 22 at its lower end and there being a bearing 23 between said nut and the upper end wall 24 of a recess 25 formed in the member 21, said recess accommodating the nut 22 and bearing 23.

It may be desirable, in some instances, to positively prevent reverse rotation of the member 21, though friction between the 30 plunger and pump barrel and between the liquid and sucker rods is ordinarily sufficient to prevent such reverse rotation, and for this reason a dog or dogs 26 are pivoted at 27 to the lower section 12. When it is 35 desired to throw any one or all of the pawls 18 and dogs 26 out of engagement with the teeth 20, the said pawls and dogs may be swung upwardly and engaged with racks 28 which, in this instance, are U-shape and constructed of wire and have their opposite 40 ends passing through the pivots on the pawls and dogs. The racks 28 project laterally from the pivots 19, 27.

The lower portion of the member 21 is 45 provided with a slot 29 and with a pin 30 which extends across said slot, the projecting ends of said pin being provided with cotter pins 31 to prevent the pin 30 slipping out of the member 21.

50 It is to be understood that any suitable means may be provided connecting the member 21 to the cable, indicated at *d* in Fig. 1 and, in this instance, said means is preferably constructed as follows: Pivots 55 connected by the pin 30 to the member 21 is a pair of hook-shape members 32, the open sides of the hooks being turned toward a plane intersecting both hooks when closed together. The members 32 thus overlap so 60 that both support the cable *d*. The cable *d*, when engaged with the hooks, prevents swinging of the hooks away from one another. When the hooks are swung away from one another, they become spaced sufficiently 65 at their lower ends to admit of the

entrance or exit of the cable *d*, but when the members 32 are closed together, the cable rests in both hooks and each hook will prevent removal of the cable from the other, as the backs of the hooks are on opposite sides 70 of the cable. The cable *d* which is not a part of the present invention, is connected with the polish rod *c* by any suitable grip *e*.

The invention operates as follows: In this particular instance, the parts are arranged to effect rotation of the polish rod on the downstroke of the walking beam and on the upstroke of the walking beam the polish rod is not rotated. The rotary motion is thus intermittent. Assuming that the parts are in the positions indicated in Figs. 1 and 2, it will be noted that the walking beam is at the top of its stroke. As the walking beam swings downwardly, the portion 75 17 is caused to describe an arc about the fulcrum of the walking beam in a direction opposite to that indicated by the small arrow in Fig. 2 thus moving the pivots 19 of the pawls 18 toward the toothed member 21 so as to lengthen the horizontal distance from the pivots 19 to vertical planes positioned at the free ends of the pawls, causing the plate 21 to rotate to the left in Fig. 2. After the walking beam reaches the lower limit of its stroke, it swings upwardly, thus forcing the pawls in a direction indicated by the arrow in Fig. 2, the teeth 20 being shaped to catch the pawls 18, thereby effecting rotation of the member 21. It will be seen that comparatively slight 80 relative swinging between the sections 11, 12 will produce intermittent rotary motion 85 of the member 21.

If it be not desired to effect rotation of the polish rod, the pawls 18 will be thrown 90 out of engagement and rested upon the rack 28. When rotation of the polish rod is not effected, there is still a decided advantage in having the sectional stem with a pivotal connection for, on the downstroke of the walking beam, the stuffing box will tend to hold the section 12 in axial alignment with said stuffing box and polish rod while the pump plunger is forced downwardly by the 95 weight of the sucker rods and superposed liquids, the section 11 will then simply follow the section 12 without bending the polish rod.

The head 13 may be bolted or otherwise secured to the walking beam but, in this 100 particular instance, the head 13 simply rests upon the upper face of the walking beam and is free to rock, but the rocking movement is limited by the flat faces 14 which 105 thus function as stops. The weight of the 110 sucker rods and liquid in the well being pumped will tend to swing the member 11 into axial alignment with the polish rod and partly nullify relative motion between 115 the sections 11, 12 but, because of the flange 120 125 130

faces or stops 14 there is sufficient relative motion of the sections 11, 12 to effect rotation of the member 21.

Since the members 32 cannot swing open when the cable *d* is resting in the hooks, it may be of advantage in some instances to prevent the cables jumping upwardly in the hooks and for this reason the hooks are each provided on their outer edges with a pair of ears 36, the ends of each pair being on opposite sides of the cable, and passing through each pair of ears is a cotter pin 37 so that the cable will lie between the members 32 and the cotter pins 37.

15 In the form of the invention shown in Fig. 5, the parts that functionally correspond to those described above are indicated by the same reference characters with the addition of the letter *a*. In this form of the invention, the under faces of the head 13^a are convex so as to facilitate the rocking of the section 11^a on the walking beam. In order to prevent a great degree of rocking of the member 11^a relative to the walking beam that would prevent such movement of the pawl 18^a, as is requisite for effecting rotation of the polish rod, it is necessary to either limit movement of the member 11^a relative to the walking beam in the direction of the small arrow in Fig. 5 or to limit movement of the section 12^a in the opposite direction.

20 In the form of the invention shown in Figs. 1 to 4, the flat faces 14 serve as stops to limit swinging of the section 11 and, in Fig. 5, a stop 14^a projects from the section 11^a and engages the rear wall of the slot *b* of the walking beam. The stop 14^a is in the form of a pin and is adjustably mounted, being slidably mounted in a hole 33, and a set screw 34 in the member 11^a engages the stop 14^a to hold it in adjusted position. The lower portion of this modified form is the same as in Figs. 1 to 4.

25 45 As the walking beam moves on its up-stroke, the stop 14^a functions the same as the face 14 in Fig. 2 to limit swinging in the direction of the small arrow, thus insuring the requisite amount of relative motion between the members 11^a, 12^a to actuate the pawl 18^a.

50 In the form of the invention shown in Fig. 6, the parts are the same as those illustrated in Fig. 5, excepting that the stop 14^a and screw 34 are omitted and in lieu thereof there is a flexible connection 14^b secured at one end by a fastening 35 to the walking beam and at its other end to the lower stem section 12^b. In Fig. 6 the parts that function the same as those in Fig. 1 are indicated by the same reference characters with the addition of the letter *b*. The lower portion of this modified form is the same as in Figs. 1 to 4.

55 60 65 In the form of the invention illustrated

in Fig. 7, the parts that function the same as those described in Figs. 1 to 4 are indicated by the same reference characters with the addition of the letter *c*, and it will be noted that the pivot 15^c is eccentric to the longitudinal axis of the stem so that as the walking beam starts on its downstroke the arm 17^c will move in the direction of the small arrow, thus engaging the pawl 18^c in the teeth 20^c, resulting in the rotation of 75 the polish rod. A spring 36 is secured at one end to the section 11^c and the other end engages beneath a bridge 37 on the section 12^c so that the spring, put under tension on the upstroke of the walking beam, will expand on the downstroke to cause the arm 17^c to swing to the right as stated above, On the upstroke the pawl drags and the polish rod is not rotated.

70 80 85 If it be desired to effect rotation of the polish rod on the upstroke, by the hangers illustrated in Figs. 2, 6 and 7, said hangers will be taken off of the walking beam, turned through an angle of 180 degrees and then replaced on the walking beam in the new position.

I claim:

1. A beam hanger comprising a stem having upper and lower sections pivotally connected, one of said sections being provided with means to suspend it from a walking beam, the other section being provided with means to connect it with a polish rod and means operable by relative swinging in one direction between the sections to effect rotation of a polish rod.

2. A beam hanger comprising a stem having upper and lower sections pivotally connected, one of said sections being provided with means to suspend it from a walking beam, the other section being provided with means to connect it with a polish rod and means operable by relative swinging between the sections to effect intermittent rotary movement of a polish rod.

3. A beam hanger comprising a stem having upper and lower sections pivotally connected, one of said sections being provided with means to suspend it from a walking beam, the other section being provided with means to connect it with a polish rod and means operable by relative swinging between the sections to effect intermittent rotary movement of a polish rod in one direction.

4. A beam hanger comprising a stem having upper and lower sections pivotally connected, one of said sections being provided with means to suspend it from a walking beam, a toothed member rotatably mounted on one of the sections, and a pawl pivoted to the other section and adapted to intermittently actuate the toothed member as the walking beam operates.

5. A beam hanger comprising a stem

having upper and lower sections pivotally connected, one of said sections being provided with means to suspend it from a walking beam, a toothed member rotatably mounted on one of the sections, a pawl pivoted to the other section and adapted to intermittently actuate the toothed member in one direction as the walking beam oper-

ates, and a dog pivoted to the first mentioned section and holding the toothed member against rotation in the opposite direction when the pawl is being retracted.

Signed at Los Angeles, California, this 31st day of March, 1925.

JAMES P. RATIGAN.
